HIGH PRESSURE STEAM PURIFIER

William Brewster Gurney, Baton Rouge, La.

Application August 12, 1952, Serial No. 303,948

8 Claims. (Cl. 183—1)

The present invention relates to a method of and apparatus for the purification of steam, and more particularly to the method and apparatus for the removal of contaminants from saturated steam by adiabatic expansion of the steam. This application is a continuation in part of my application, Serial No. 235,872, filed July 9, 1951, and now abandoned.

High pressure steam generated for power process usually contains minor amounts of impurities such as silica and other water salts, which during the transformation of energy in an associated turbine frequently is deposited on the blade surfaces and other internal parts of the turbine. An accumulation of such deposits results in reduced turbine efficiency and loss of its availability while the deposits are being removed.

The transportation of contaminating matter by the steam is generally considered to occur either by mechanical entrainment, by vapor or solution in the steam, or by a combination of these processes. Mechanical entrainment can be reduced by efficient separation of liquid and vapor through the use of centrifugal forces, providing the physical properties of the liquid-vapor mixture are conducive to mechanical separation.

According to the Mollier diagram for steam, saturated steam at a pressure above 450 pounds per square inch absolute (p. s. i. a.) passes through a moisture zone as the steam pressure is reduced without loss of heat. Further reduction in the steam pressure causes the steam to pass through the saturated steam line into the superheated steam zone.

I have discovered that a major portion of the impurities in the steam discharged from a steam generator can be eliminated by the condensation of a small part of the steam generated. Apparently, the condensed moisture forms minute droplets about a nucleus of solid impurity present with the steam. In any event, the condensed moisture droplets are separated from the steam and withdrawn from the steam and water separators out of contact with the steam strain. The collected water contains a major portion of the impurities present in the saturated steam generated in the unit, including a high percentage of silica.

The condensation of moisture in steam can be accomplished by a reduction in pressure of the steam. The steam pressure reduction may be adiabatic and effective when the dry saturated steam pressure is in excess of 450 p. s. i. a. The expansion of the steam can be accomplished by flow through an orifice, nozzles, or the like.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described an embodiment of the invention.

Of the drawings:

Fig. 1 is a transverse view, in section, of a steam and

2

water drum incorporating an embodiment of the invention;

Fig. 2 is a partial transverse section of a steam and water drum showing a modified form of the invention;

Fig. 3 is a somewhat diagrammatic view of a steam and water drum and a superheater inlet header incorporating structure according to the invention;

Fig. 4 is an enlarged view of a portion of the apparatus shown in Fig. 3;

Fig. 5 is a diagrammatic view of a steam purity testing apparatus containing structure according to the principle of the present invention; and

Fig. 6 is a plan view of a portion of the apparatus shown in Fig. 5.

Referring to Fig. 1, the invention is exemplified as installed in the steam and water drum 10 of a steam generating unit. A mixture of steam and water is delivered through tubes 11 to the drum 10, water passes from the drum through downcomer tubes 12 into the circulating system of the steam generating unit, while saturated steam is discharged through rows of tubes 13 positioned in the upper portion of the drum 10. The steam and water mixture entering the tubes 11 discharges into a chamber 14 which is formed by a series of connected plates 15 mounted internally of the boiler drum. A series of horizontally spaced vertical elongated ducts 16 connect chamber 14 with a row of cyclonic steam separators 17. The general construction of the cyclonic type separator and the connecting chamber 14 is disclosed in detail in U. S. Patent 2,368,211.

As described in the patent and shown in Fig. 1, each separator is provided with a bottom outlet 18 at the lower end and an upper outlet 20 at the upper end thereof. Steam and water are separated within the separators 17 by centrifugal forces with the steam passing upwardly through the outlet 20 and the separated water discharging downwardly through the outlet 18. Ordinarily the water level within the drum 10 is maintained approximately at the horizontal center line of the drum. The water level may vary above or below the drum center line in the course of operations, but should not vary beyond the general limits of the heights of the cyclonic separator 17.

The steam leaving the outlet 20 of the cyclonic separators is substantially dry and in a saturated condition, although it is possible for the steam to be slightly superheated, saturated, or to contain a small amount of moisture. The moisture would be in the form of minute droplets which are extremely difficult to separate from the steam by ordinary mechanical means.

The steam passing through the cyclone separators 17 and toward the tubes 13 is directed through a secondary steam and water separator 21. The secondary separator is formed from a series of corrugated plates arranged in parallel and lying in a series of planes generally perpendicular to the longitudinal axis of the drum 10. This construction is well known. On the steam entry side of the separator 21 is positioned a plate 24 which is provided with a plurality of orifices 25. Inwardly of the separators 21 is a dry steam collecting chamber 22 opening directly to the tubes 13. The lower portions of the separators 21 are provided with a moisture collecting chamber 23 and plates 26. In the construction described, the steam passing through the orifices 25 expands with the condensation of moisture therein which is collected by contact with the corrugated plates of the secondary separators. The moisture collecting upon the separator plates flows downwardly into the chamber 23 and thence through discharge pipes 27 which open to the lower portion of the drum 10 beneath the surface of water maintained therein.

The expansion of the steam with the condensation of

moisture therein produces droplets having sufficient dimensions to be trapped by the separator plates and removed from the moving stream so that the steam discharging through the tubes 13 is substantially dry and of a high purity.

The alternate construction shown in Fig. 2 illustrates a somewhat different type of steam separating means. As shown, the shell 40 of the steam and water drum is provided with steam, or steam and water mixture, supply tubes 41 and steam outlet tubes 42. The steam entering through the tubes 41 passes downwardly and around the edge of baffle plates 43 to enter a steam and water separator 48 through a plate 44 having a multiplicity of perforations 39 therein. In passing through the perforations of the plate 44 the steam is expanded with the 15 condensation of moisture therein. The moisture is separated from the steam in the separator 48, which may be of the general type previously described in connection with the separators 21 shown in Fig. 1. The steam leaving the separators 48 passes through a perforated plate 45 before entering the steam outlet tubes 42. As shown, the separators are supported from upper plates 47 attached to the shell 40 and a lower structure which includes a longitudinally extending plate 46 and a series of radial drain passageways 50 forming a bottom closure 20 and leading to a discharge pipe 51. The pipe 51 extends downwardly from the mid-point of the structure and the passageways 50, and is provided with a valved branch connection 53 terminating beneath the water level maintained in the drum, and a valved branch connection 52 25 which extends through the shell 40 of the drum.

The structure shown in Fig. 2 is primarily intended to receive substantially dry steam through the tubes 41, as for example where the drum defined by the shell 40 represents the steam drum of a steam generating unit having multiple steam and water drums. However, a mixture of steam and water from steam generating tubes can be delivered to the drum through the tubes 41 with the separator 48 removing moisture from the steam. Under the latter circumstances, the tubes 42 may discharge to an external device for further steam expansion and removal of the steam impurities in the moisture condensed therefrom.

The apparatus shown in Fig. 3 schematically illustrates a steam and water drum 60 having steam inlet pipes 61 opening to a primary steam and water separator 64. The separator 64 may be of the general cyclonic type described in Fig. 1. The substantially dry steam leaving the separator 64 passes through a secondary separator 65 in its flow toward the steam outlet tubes 63. The water separated from the steam in the primary separator is discharged downwardly beneath the level 68 of the water maintained in drum 60. The moisture separated from the steam by the secondary separators 65 discharges through a drainpipe 66 to either of the valved branch pipes 67 or 70. The branch drainpipe 67 discharges the moisture outside of the boiler drum, while the branch pipe 70 discharges the moisture beneath the level 68 of the water. The substantially dry steam leaving the drum 60 through the tubes 63 tangentially enters a cylindrical vessel 71 where the moisture is separated from the steam by centrifugal force. The collected moisture is discharged from the bottom of the vessel 71 to the atmosphere through the valved pipe 74 or to a reservoir 76 through the valved pipe 75. The steam passes around the lower end of a centrally located cylindrical baffle 72 positioned in the upper portion of the vessel 71 to discharge through a tube 73 which opens into a superheater inlet header 77.

The superheater inlet header 77 is illustrated in Figs. 3 and 4, where the entering steam from the tube 73 passes in a generally radial direction as directed by a baffle 85 toward an axially disposed manifold 83. The manifold is provided with a series of longitudinal spaced inlet ports 87 and a series of radially disposed exhaust tubes 84.

The tubes extend through and beyond the wall of the header 87 and are overlappingly engaged by a corresponding series of tubes 78 which are welded to the header 77 and connected with the legs of a superheater (not shown).

The longitudinal baffle 85 is attached to a longitudinally extended perforated baffle which follows, in general, the contour of the header 77 and is attached at its opposite end to the wall of the header 77 adjacent the tubes 84. The steam entering through the tubes 73 is expanded with the moisture formed by the expansion of the steam passed through the perforations of the plates 86, for discharge through a drainpipe 81. The pipe 81 opens to a reservoir 82 and is further provided with a branch by-pass pipe 80 opening to the atmosphere. Both of the pipes 81 and 80 are provided with valves to control the flow of steam through either.

As herein before described, several methods of obtaining a suitable expansion of high pressure saturated steam are possible. Each of the described arrangements of apparatus will attain the purity results advantageously accomplished by the invention. It will be appreciated that the reduction in pressure necessary for steam purification is greater than the ordinary pressure reduction obtained in passing saturated steam through the customary steam and water separators. In general, the steam purification feature of the invention is applicable to saturated steam at an initial pressure in excess of 450 p. s. i. a. At each of the steam pressures above that given, a reduction in pressure will result in the formation of a mixture of steam vapor and liquid water because the latent heat of the vapor is higher at the reduced pressure. For example, the approximate maximum moisture content in saturated steam, assuming adiabatic expansion, can be attained at a lower pressure according to the following table:

Initial Pressure, p. s. i. a.	Approx. Reduced Pressure, p. s. i. a. for max. moisture of condensation	Approx. Percent Moisture obtained by pressure reduction
450	440	Slight
860	450	1.0
1,050	490	2.0
1,160	500	3.0
1,350	520	4.0

An example of the calculations used in determining the above moisture figures is as follows:

Moisture increase due to drop in steam pressure from 775 p. s. i. a. to 650 p. s. i. a.

p. s. i. a.	Total heat in B. t. u. per pound from 32° F.	Heat in Liquid at saturation temperature in B. t. u. per pound	Latent heat in B. t. u. per pound
650	1,202.3	481.8	720.5
775	1,199.3	505.3	694.0

(Assume the 775 p. s. i. a. saturated steam to contain 2% moisture. Let X equal the unknown moisture content present at 650 p. s. i. a., after adiabatic expansion of the saturated steam.)

55 $505.3 + 694.0 (1.00 - 0.002) = 481.8 + 720.5 (1.00 - X)$
 $23.5 - 26.5 - 1.388 = -720.5X$
 $X = 4.388/720.5 = 0.00608 \text{ or } 0.61\%$
 $0.608 - 0.2 = 0.408\% \text{ increase in moisture due to the steam pressure dropping from 775 p. s. i. a. to 650 p. s. i. a.}$

I have found that it is not necessary to reduce the pressure of the saturated steam as much as indicated in the above table, for example, a reduction in pressure from 75 650 to 645 p. s. i. g. caused sufficient condensation of

moisture in the steam to remove a large portion of the impurities, particularly silica, in the saturated steam.

As shown in Fig. 5 the principle of expanding steam to produce moisture therein, and separating and collecting the moisture with the steam impurities therein can be used for test purposes. As shown in the drawing, a steam header 91 is provided with a sample nozzle and collecting pipe 92 leading tangentially into a closed cylindrical vessel 90. The pipe 92 is provided with throttle valves to regulate the flow and pressure drop of steam from the nozzle into the vessel 90. The vessel is provided with a cylindrical baffle 88 positioned in the upper part of and depending from the top of the vessel and surrounding the steam outlet pipe 93. A water discharge pipe 95 is connected to the bottom of the vessel 90 and connects with a conventional degassing and conductive test apparatus 96. The steam pipe 93 leads to a corresponding degassing and conductive test apparatus 97. With the apparatus described a sample of the steam passing through the pipe 91 is discharged at a reduced pressure into the vessel 90 so that the condensation recovered from the condensed steam is directed to one test apparatus while the steam remaining from the sample is directed to a companion test apparatus whereby the conductivity of both the purified steam and the contaminated moisture obtained from the steam sample can be compared.

The portion of Fig. 5 relating to steam conductivity test apparatus and identified by numerals 96 and 97 is well known and is described in the Transactions of the A. S. M. E., November 1940, vol. 62, No. 8, on page 728.

It will be noted that in all phases of the invention, saturated steam in a substantially dry condition is expanded to condense moisture therein, the condensed moisture is separated from the steam and discharged out of contact with the remaining steam flow. A major portion of the impurities in the steam will be present in the condensed moisture, and the steam discharging from the apparatus will be in a substantially pure condition.

While in accordance with the provisions of the statutes I have illustrated and described herein preferred embodiments of the invention, those skilled in the art will understand that changes may be made in the method of operation and form of the apparatus disclosed without departing from the spirit of the invention covered by my claims, and that certain features of the invention may sometimes be used to advantage without a corresponding use of other features.

What is claimed is:

1. Apparatus for purifying steam which comprises means for separating entrained water from saturated steam, means for adiabatically expanding the substantially dry saturated steam for the condensation of moisture therein, and means for separating the condensed moisture from said expanded steam.

2. Apparatus for purifying steam comprising a source of generally dry saturated steam, nozzle means for the expansion of said steam whereby moisture is condensed therein, steam and water separating means in the flow path of said expanded steam, and means for the separate discharge of collected moisture therefrom.

3. Apparatus for purifying steam comprising a steam and water drum having a steam outlet in the upper portion thereof and tubes opening to said drum for the admission thereto of a mixture of steam and water, steam and water separators within said drum for the upward flow of generally dry steam therefrom, nozzle means for the expansion of said steam within said drum whereby moisture is condensed from said steam, and means for collecting and discharging said condensed moisture out of the path of said expanded steam.

4. In a steam and water drum having a steam outlet in the upper portion and a water outlet in the lower portion thereof, means for supplying a mixture of steam and water to said drum, steam and water separating means within said drum arranged to receive the steam and water

mixture supplied to said drum, said separating means discharging substantially dry steam into the upper portion of and water into the lower portion of said drum, closely spaced baffle plates forming a secondary steam and water separator in the upper portion of said drum interposed in the flow path of steam toward said upper drum outlet, an orifice plate positioned in the path of the dry steam entering said secondary separator, and means for collecting separated water from said secondary separator and discharging said collected water into the lower portion of said drum.

5. In a steam generator having a steam and water drum, means for supplying a steam and water mixture to said drum, means within said drum for separating entrained water from said steam, secondary steam and water separating means external of said drum arranged to receive the steam discharged from said drum, a superheater inlet header arranged to receive the steam from said secondary separator, means within said header for condensing a minor portion of said steam and separating the condensed moisture from the remainder of said steam, and means for removing said separated moisture from the superheater inlet header out of the flow path of said steam.

6. In a steam generating and superheating unit, a steam and water drum, means for supplying a steam and water mixture to said drum, means within said drum for separating entrained water from said steam, a secondary steam and water separator external of and arranged to receive the steam discharged from said drum, said secondary separator including a closed cylindrical vessel having a tangential steam inlet duct and centrally located top and bottom outlets for steam and water respectively, a superheater inlet header arranged to receive the steam from said secondary separator means within said header for condensing a minor portion of said steam and separating moisture from the remainder of said steam, and means for removing said separated moisture from the superheater inlet header out of the flow path of said steam.

7. The method of purifying substantially dry saturated steam having a pressure in excess of 450 p. s. i. a. which comprises the steps of adiabatically expanding said steam to condense moisture therein, and separating the condensed moisture from the flow path of said expanded steam.

8. The method of determining the purity of substantially dry saturated steam having a pressure in excess of 450 p. s. i. a. which comprises the steps of adiabatically expanding a sample of said steam to condense moisture therein, separating the condensed moisture from said expanded steam, and separately testing the condensed moisture and the expanded steam for electric conductivity to determine the impurities in said steam sample.
